DESIGN FOR A BATTERY SELECTOR

Dorac B. Banta, Bloomfield, N. J., assignor to
Thomas A. Edison, Incorporated, West Orange,
N. J., a corporation of New Jersey

Application November 7, 1935, Serial No. 59,426

Term of patent 7 years

To all whom it may concern:

Be it known that I, Dorac B. Banta, a citizen of the United States, residing at Bloomfield, in the county of Essex and State of New Jersey, have invented a new, original, and ornamental Design for Battery Selectors, of which the following is a specification, reference being had to the accompanying drawing, forming a part thereof.

Fig. 1 is a plan view of a battery selector, showing my new design, with the slide thereof in one position of adjustment;

Fig. 2 is a view similar to Fig. 1, but with the slide of the battery selector in another position of adjustment;

Fig. 3 is a view in side elevation of the battery selector as shown in Fig. 1;

Fig. 4 is a view in end elevation of the battery selector looking from the left in Fig. 1; and

Fig. 5 is a view in end elevation of the battery selector, looking from the right in Fig. 1.

The characteristic features of my design reside in the shape, disposition and grouping of indicia marks substantially as shown.

I claim:

The ornamental design for a battery selector, as shown and described.

DORAC B. BANTA.
